TELEVISION ANTENNA

Pete Kuldin, 8891 Stout, Detroit, Mich. 48228

Filed Nov. 14, 1974, Ser. No. 524,294

Term of patent 14 years

Int. Cl. D14—0.3

U.S. Cl. D26—14 F

FIG. 1 is a front elevational view of a television antenna showing my new design;

FIG. 2 is a fragmentary sectional view thereof taken along the line 2—2 in FIG. 1 and looking in the direction of the arrows; and

FIG. 3 is a perspective view thereof.

The bottom of the television antenna is flat and unornamented.

The characteristic feature of my design resides in the specific configuration of the upper portions of the dipoles.

I claim:

The ornamental design for a television antenna, substantially as shown and described.
